UNITED STATES PATENT OFFICE

2,566,003

ANCHORING DEVICE FOR COAL AND OTHER MINES

Walter Vogel, Santiago de Chile, Chile, assignor to Mavor & Coulson, Limited, Glasgow, Scotland

Application October 2, 1948, Serial No. 52,530
In Great Britain July 7, 1947

1 Claim. (Cl. 262—8)

1

This invention relates to a machine of a previously proposed kind for mining coal and other minerals in which the machine comprises a transportable vehicle having mineral-splitting means for wedging off the mineral from a seam and in which the vehicle is advanced stepwise by a hydraulic cylinder-and-ram propulsion unit working against an anchoring device.

The object of the present invention is to provide an improved anchoring device which will exert on the mine floor and roof a grip that increases in some proportion to any increase in the force exerted on the device by the machine that it serves to anchor and which in the stepwise advance of the machine will quickly take its grip in each new position and will easily release itself for the next advance from that position.

According to the invention, in a machine of the kind stated in which the propulsion unit includes a reciprocable hydraulic ram, the anchorage device comprises slidable lower and upper shoe engageable with a mine floor and roof respectively, lower and upper links to which said shoes are pivotally connected respectively and which are inter-connected by a pivotal joint inter-connecting said links and connecting them to said ram, said links being angularly related to act as a toggle linkage, and means acting on said links to widen their angular relationship and thus cause engagement of the roof by the upper shoe.

Means are provided for limiting the range of variation of the angular relationship between the upper and lower links. The extent of variation is such that the maximum widening of the angular relationship between the upper and lower links is less than 180°.

Preferably in order to maintain approximate constancy in the height of the joint in relation to the floor, the lower link is a simple non-extensible link; whereas on the other hand, in order to allow for substantial adjustment such as will be required to suit roofs of different heights, the upper link is extensible in length.

The invention is illustrated by the accompanying diagrammatic drawing, in which: Fig. 1 is an elevation of an example of the anchoring device applied to a coal-mining machine, and Fig. 2 is a corresponding plan. Fig. 3 is a detail view.

The anchoring device shown is connected to a coal-mining machine of the kind stated in which the machine is a transportable vehicle characterised by a leading wedge 10 that is thrust forwards in the manner of a chisel to cut in a vertical plane parallel to and behind the coal face,

the vehicle being advanced stepwise by a hydraulic cylinder-and-ram unit 11, 12, which is mounted on the frame 13 of the vehicle and advances the vehicle by pushing against the anchoring device. In the example, the end of the hydraulic ram 12 is pivotally connected to a joint pin 14 incorporated in the anchoring device.

The machine shown includes a driving motor 15, a hydraulic pump 16 driven from the motor through gears 17, a tank 18 for hydraulic fluid (usually oil), and a distributing valve 19 to control the supply of oil between the cylinder 11, pump 16 and tank 18. Pipes 20 lead from the valve 19 to opposite ends of the cylinder 11.

The machine shown also includes in addition to the wedge 10, co-planar upper and lower wedges 21 and 22 for stripping off coal above and below the level dealt with by the wedge 10 in front, a shovel-like cutter 23 for scooping up coal from the mine floor A, and an adjustable roof-cutter 24 for stripping down coal from the mine roof B. The components 22 and 23 co-operate to lift and deflect outwards such coal as may be scooped up.

The constructional details of the machine form no part of the present invention, the machine being described herein to illustrate a use to which the anchoring device can be put and as an illustration of a mining machine in combination with which the anchoring device can be used.

The anchoring device comprises mainly a jack assembly consisting of a double upper link 25 and a single lower link 26 jointed to the link 25 by the pin 14.

The foot and the head of the jack assembly respectively consist of flat-faced slidable shoes 27 and 28, each of which is pivotally connected by a pin 29 or 30 to the upper or lower link of the device. The lower shoe 27 is made as a substantial sole plate. The upper component 25 consists of two screw-jack units each of which can be extended and contracted lengthwise in a manner usual with screw jacks. The lower link 26 is a non-extensible link, which may be much shorter

than the screw-jack units, when fully contracted, to suit the comparatively low level at which it is preferable to arrange the cylinder-and-ram unit 11, 12. The joint of the anchoring jack assembly, namely the pin 14, interconnects the hydraulic ram 12, the upper link 25 and the lower link 26, the arrangement being such that said links can vary their angular co-relationship and also such that the joint is maintained at a constant level in relation to the ground despite changes in such co-relationship. This arrangement may consist

55

in providing a short vertical slot 12A in the ram end, the slot being penetrated by the pin 14.

Provision may be made for limiting the range of change in the angular relationship between the link 25 and the link 26. The arrangement, for instance, might be such that when the upper and lower links 25, 26 adopt their widest co-relationship, they are about 175° apart; and, when they adopt their closest co-relationship, they are about 130° apart. These two limits are defined by any appropriate stops. Such limit stops, in the example, are provided by a pair of struts 31 pivotally connected to extensions 32 of the shoe 27, there being one strut to each jack-unit of the link 25. Each strut is made with a fork portion 33 having holes 34 through any two of which two limit pins 35 may be inserted. Each jack unit passes through the fork portion 33 of one of the struts 31, so that the pins 35 are engaged by the jack-unit at the limits of its range of angular movement in relation to the lower link 26.

Means are provided for urging the upper and lower links 25, 26 lightly apart. In the example, the means provided (shown only in Fig. 1) include a two-limbed spring 36 anchored to a bracket 37 on the shoe 27, one limb pressing against the link 25 and the other limb pressing against the link 26. The spring means also include a blade spring 38 which is anchored to a pin 39 on the shoe 27 and presses in the link widening direction upon the joint incorporating the pin 14. These spring means urge the upper and lower links apart so that they tend to exercise a comparatively light grip on the floor A and roof B.

In operation, the anchoring device is placed in a selected position by appropriate manoeuvring of the wedge machine, and the screw-jack units of the upper link are extended to suit the roof height. The anchoring device, thus adjusted, lightly grips the floor A and roof B. The valve 19 is manipulated so that the hydraulic ram 11 of the wedge machine is thrust powerfully rearwards, the force being applied directly to the joint 14 of the anchoring device, which therefore extends as the angular relationship between its upper and lower links 25, 26 widens. In accordance with the well-known toggle-link principle, the gripping force exercised by the foot and head 27 and 28 of the device greatly increases as the angular co-relationship widens under the force

applied by the ram 11. A point is reached at which the device grips the floor and roof with adequate strength, and thereupon the wedge machine is advanced to do its work upon the coal seam.

At the end of the working stroke of the machine, the valve 19 is manipulated so that the ram 11 is drawn forwards so that the anchoring device is caused to relieve its grip between the floor and roof. A point is reached at which the anchoring device slides, being pulled forwards by the ram into a new position, in readiness to provide an anchorage for the next working stroke.

An especial advantage of an anchoring jack according to this invention, when used in combination with a wedge-cutting machine, is that the jack is transported quickly from position to position without need for adjusting it to slacken its grip and re-adjusting it to take a new grip.

I claim:

A mining machine of the kind stated in which the propulsion unit includes a reciprocable hydraulic ram, said machine having an anchorage device comprising slidable lower and upper 25 shoes engageable with a mine floor and roof respectively, lower and upper links to which said shoes are pivotally connected respectively, a pivotal joint inter-connecting said links and connecting them to said ram, said links being angularly related to act as a toggle linkage, means 30 acting on said links to widen their angular relationship and thus cause engagement of the roof by the upper shoe, and means for limiting the range of varying the angular relationship between the lower and upper links, said means comprising a strut which is pivotally connected to one of the shoes and which has stops engageable by the upper link at the ends of a predetermined range of movement.
